United States Patent Office

Des. 216,863
Patented Mar. 17, 1970

216,863

GRAIN SHOVEL

Gabe J. Landreville, 1913 Carroll Ave.,
St. Paul, Minn. 55104

Filed July 8, 1968, Ser. No. 12,657

Term of patent 7 years

Int. Cl. D8—01

U.S. Cl. D8—10

Fig. 1

Fig. 2

Fig. 3

Fig. 4

FIG. 1 is a top view of the grain shovel, showing the embodiment of my new design;

FIG. 2 is a right side view;

FIG. 3 is a bottom view; and

FIG. 4 is a front view.

The left side is a mirror image of the right side.

I claim:

The ornamental design for a grain shovel, as shown and described.
